UNITED STATES PATENT OFFICE.

LESLIE E. TRIMM, OF BROOKLYN, NEW YORK.

TENT AND HAMMOCK.

1,343,800.

Specification of Letters Patent. Patented June 15, 1920.

Application filed March 25, 1919. Serial No. 285,059.

To all whom it may concern:

Be it known that I, LESLIE E. TRIMM, a citizen of the United States, and a resident of the city of New York, borough of Brooklyn, in the county of Kings and State of New York, have invented a new and Improved Tent and Hammock, of which the following is a full, clear, and exact description.

10 This invention relates to a combined tent and hammock and has for an object the provision of an improved construction wherein the device may be used in its combined capacity as tent and hammock, or 15 may be used separately to a limited extent.

Another object of the invention is to provide a tent and hammock arranged to be supported by ropes instead of the usual poles, the arrangement being such that the 20 hammock associated with the tent may be used as a bed in the tent, or as a canopy or fly for the front of the tent.

A further object of the invention is to provide a tent and hammock arranged with 25 fittings at the ends which are substantially identical whereby either of these devices may be supported by cables, ropes or the like connected thereto and to suitable trees or supports.

30 In the accompanying drawings:

Figure 1 is a longitudinal vertical section through a tent and hammock disclosing an embodiment of the invention, the same being shown ready for use.

35 Fig. 2 is a transverse section through Fig. 1 on line 2—2.

Fig. 3 is a plan view on an enlarged scale of one end of the hammock embodying certain features of the invention.

40 Fig. 4 is an enlarged sectional view through Fig. 3 on line 4—4.

Fig. 5 is a fragmentary top plan view of one end of the tent shown in Fig. 1, illustrating the reinforcement and the connecting fitting.

45 Fig. 6 is a sectional view similar to Fig. 1, showing a slightly modified form of the invention.

Fig. 7 is a transverse sectional view 50 through Fig. 6 on line 7—7.

Referring to the accompanying drawings by numerals, 1 indicates the tent in its entirety and 2 the hammock in its entirety.

The tent 1 may be made of any suitable canvas, or other material, preferably light can-

vas or some other light material which will answer the purpose, also preferably the tent is made A-shape as shown in Fig. 2 with front and rear ends 3 and 4 open down the center and provided with tying members 5 and 6. The bottom edge of the tent and also the end members are provided with suitable apertures 7 through which looped pieces of rope may be inserted if desired for accommodating pins, though quite often 65 this is not necessary. The upper part of the tent, or apex thereof, is not provided with the ordinary ridge pole now in common use, but a strip of canvas or other reinforcing material 8 and provided with a 70 looped portion at each end which is looped over the straight section 11 of the eyelet 9 and clamped in position by rivets 10. This arrangement allows the strain on the eyelet 9 to be communicated to the full length 75 of the strip 8 as well as to the tent 1. The eyelet 9 (Fig. 5) is preferably made of metal and is provided with converging sections 11 extending from the straight section 12 and merging into a ring section 13 80 for receiving the ropes 14. These ropes may be tied or secured in any desired manner to the eyelet 9 and then passed around suitable supports, as for instance trees 15 and 16. Preferably the ropes 14 are brought 85 under some considerable tension so as to hold the apex of the tent substantially in a straight line. In forming the tent, if desired suitable pockets 17 may be stitched thereon or secured thereto in any desired 90 manner.

Preferably the tent is made of a size to easily accommodate one person when camping and also accommodate the usual supplies and paraphernalia that go with a camping 95 outfit. However, the tent may be made much larger to accommodate more than one person, or even smaller to be arranged as shown in Figs. 6 and 7 hereinafter fully described.

100 Associated with the tent 1 is a hammock 2 which is made from strong canvas or other suitable material and adapted to act as a hammock as shown in Fig. 1 in full lines, or as a fly as shown in dotted lines. The 105 hammock is arranged on each end as shown in Figs. 3 and 4, namely with a turned over portion 18 fitting over the straight section 19 of the eyelet 20, which eyelet has a rounded or ring section 21 for receiving the 110

rope 22. The ropes 22 are passed around the trees 15 and 16 and tied or secured in any desired manner so that the hammock 2 will be properly positioned for receiving 5 the person occupying the tent. In order to prevent undue collapsing of the hammock 2 a bracing rod 23 is arranged at each end as shown in Figs. 3 and 4, said bracing rod extending through suitable retaining loops 25 10 into the socket of the fitting 26. This fitting is provided with a pin 27 extending through the eyelet 28, which eyelet is secured to the edge of the hammock 2 in any desired manner. 15 In Figs. 6 and 7 a slightly modified form of the invention is disclosed in which the hammock 2 is utilized in the usual way with the ropes 22, but the tent 29 is made much smaller than tent 1, though otherwise of 20 identical construction. The ropes 14 act to hold the tent 29 in position so as to cover the hammock, but to fall short of the ground. In this form of the invention a person sleeping out of doors can use the 25 hammock and be protected against the dew or slight showers, as well as cover the hammock by the tent 29 which is small and may be easily carried about. To prevent the wind from blowing the tent 29 out of place suitable 30 retaining cables or cords 30 are provided which are secured to the ropes 22, and the ends of the cords 30 are provided with hooks 32 and 33, said hooks being passed over the ropes 14 whereby the parts are held in a 35 certain definite relationship to each other. The tent 29 is provided with ends similar to ends 3 and 4 of tent 1 and in addition is provided with one or more connecting cables 34 at the lower end, said connecting 40 cables being preferably passed beneath the hammock 2 whereby the parts are positively prevented from becoming separated when in use. 45 It is to be understood that any kind of a rope may be tied or otherwise secured to the hammock or tent if desired, but preferably either the single end or the double end of a rope is used in connection with the fitting or eyelet 20 or the eyelet 9. It will be noted 50 that the portions 13 and 21 respectively of these two eyelets are made so that the rope may be passed in between the restricted portions thereof, and if the rope is provided with a knot it will strike the portions 13

and 21 respectively and thereby support the 55 hammock or tent. This arrangement of supporting the hammock or tent through the use of a knot resting against the eyelet is especially convenient as the hammock or tent may be quickly and easily taken down 60 or set up and in addition the length of the rope may be varied quickly so as to cause the hammock to be supported at the proper height. The arrangement is designed to have a special rope accompany the hammock 65 and tent which is usually long enough to have a double strand extend from the hammock to a tree or other support so that two knots may be utilized in the eyelets 9 and 20 respectively. However, if the supporting 70 tree or other support is some considerable distance away from the hammock a single rope may be used and a single knot utilized in connection with the eyelets.

In addition to the supporting ropes 22 75 for the hammock a retaining rope 30 is provided which may be arranged as shown in dotted lines in Fig. 1 when the hammock is used as a fly, or may be used as shown in Fig. 6 when utilizing the tent 29. This rope 80 is comparatively small, as there is not much strain thereon, whereas the remaining ropes are amply strong to act in the desired capacity.

What I claim is:

1. A combined tent and hammock comprising a tent structure, a hammock structure, and a single supporting cable at each end, one end of each of the cables being connected with the apex of the tent structure 90 and the other end to the end of the hammock whereby the weight of the hammock and anything supported thereby will act to stretch the apex of the tent and hold the tent in proper position. 95

2. A combined tent and hammock comprising a body substantially A shape in cross section, a hammock arranged in the body adjacent the base, cables connected to the ends of the hammock and to the apex of 100 the body acting as supports for the hammock and the body, and a retaining rope at each end of the hammock, said ropes being connected to the hammock at one end and at the opposite end to the respective 105 cables adjacent the apex of said body.

LESLIE E. TRIMM.
